3 - AUGUST SWEDBERG

By Watson E. Coleman

Attorney

UNITED STATES PATENT OFFICE.

AUGUST SWEDBERG, OF KINGSTON, PENNSYLVANIA.

SPRING-WHEEL.

1,247,177.

Specification of Letters Patent. Patented Nov. 20, 1917.

Application filed July 5, 1917. Serial No. 178,856.

To all whom it may concern:

Be it known that I, AUGUST SWEDBERG, a citizen of the United States, residing at Kingston, in the county of Luzerne and State of Pennsylvania, have invented certain new and useful Improvements in Spring-Wheels, of which the following is a specification, reference being had to the accompanying drawings.

10 This invention relates to certain improvements in spring wheels and has relation more particularly to a device of this general character including a cushioned inner hub, and it is an object of the invention to provide a device of this general character with novel and improved means whereby a positive driving connection is had between the cushioned inner hub and the wheel proper.

15 The invention consists in the details of construction and in the combination and arrangement of the several parts of my improved spring wheel wherein certain important advantages are attained and the device rendered simpler, less expensive and 20 otherwise more convenient and advantageous for use, as will be hereinafter more fully set forth.

The novel features of my invention will hereinafter be definitely claimed.

25 30 In order that my invention may be the better understood I will now proceed to describe the same with reference to the accompanying drawings, wherein:

Figure 1 is a fragmentary view in elevation of the central portion of a wheel constructed in accordance with an embodiment of my invention, certain of the parts being removed;

Fig. 2 is a fragmentary view in elevation of the central portion of my improved wheel as herein disclosed, the opposite side of that of Fig. 1 being shown, certain of the parts being also omitted.

Fig. 3 is a sectional view taken substantially on the line 3—3 of Fig. 2.

As disclosed in the accompanying drawings 1 denotes a suitably driven axle on which is mounted the inner hub 2. Surrounding the inner hub 2 and spaced therefrom is the outer hub 3 having one marginal portion provided with the inwardly directed annular flange 4 for overlying the adjacent side face of the inner hub 2 and affording

a central opening 5 to permit universal movement of the outer hub member 3 relatively to the inner hub 2 and the axle 1. 55

Interposed between the inner hub 2 and the outer hub 3 are the expandable members 6 serving to maintain the outer hub 3 substantially concentric to the inner hub 2 when the wheel is free of load. The expandable members 6 as herein disclosed each comprises a conventional type of coil spring having their opposite extremities 7 in the same general direction and in parallelism. The extremities or end portions 7 are insertible within the transversely disposed and radially alined sleeves or barrels 8 arranged on the opposed faces of the inner hub 2 and the outer hub 3. Produced in the outer faces 70 of the flange 4 is a radial groove or recess 9 of a width equal to the diameter of the opening 5. Extending within the groove or recess 9 is a plate 10 having side walls converging toward the hub 11 arranged at 75 the inner end of the plate 10, said hub being of a diameter materially less than the diameter of the opening 5. The outer end portions of the sides of the plate 10 contacting with the side walls of the groove 70 or recess 9 and it is preferred that the outer end portions of the sides of the plate 9 be rounded as indicated at 12 so that the plate 10 may have rolling contact with the side walls of the groove or recess 9. 80

The hub 11 is keyed as indicated at 14 to the axle 1 whereby the plate 10 moves in unison with the rotation of the axle 1 and the contact of said plate with the side walls of the recess or groove 9 results in a positive drive of the outer hub 3 or the wheel proper. 85

Keyed or otherwise affixed to the peripheral portion of the flange 4 is the brake hub 15 having the outwardly directed marginal flange 16 suitably secured to the wheel proper and also provided intermediate its length with the inwardly directed annular flange 17 overlying the outer face of the flange 4. 90

Engaged with the outer face of the wheel proper is the annular plate 18 overlying the outer face of the inner hub 2 and provided with an outstanding annular flange 19 with which a dust cap 20 is engaged. Engaged 105 with the outer end portion of the axle 1 is

a sleeve 21 keyed as at 22 to the axle 1. The inner end of the sleeve 21 is provided with the outstanding annular flange 23 which overlies the inner portion of the annular plate 18. Detachably engaged with the outer end of the axle 1 is the cap 24 which serves to hold the key 22 against accidental displacement.

From the foregoing description, it is
10 thought to be obvious that a spring wheel
constructed in accordance with my invention
is particularly well adapted for use by
reason of the convenience and facility with
15 which it may be assembled and operated
and it will also be obvious that my invention
is susceptible of some change and modification
without materially departing from the
appearance and spirit thereof and for
this reason I do not wish to be understood
20 as limiting myself to the precise arrangement
and formation of the several parts herein

shown in carrying out my invention in practice except as hereinafter claimed.

I claim:

A spring wheel comprising an inner hub, 25
an outer hub, cushioning means interposed
between said hubs, an axle upon which the
inner hub is mounted, an inwardly directed
flange carried by the outer hub, said flange
being provided with a radial groove, the 30
side walls thereof being substantially parallel,
and a plate secured to the axle and extending
within the groove, the sides of the
plate converging inwardly, the outer end
portions of the sides of the plate being 35
rounded.

In testimony whereof I hereunto affix my
signature in the presence of two witnesses.

AUGUST SWEDBERG.

Witnesses:

W. H. CHAPIN,
CARL H. LYNN.
